UNITED STATES PATENT OFFICE.

JOHN H. DALE, OF NEW YORK, N. Y.

ELECTRIC-LIGHTING FIXTURE.

1,160,860.

Specification of Letters Patent. Patented Nov. 16, 1915.

Application filed November 19, 1914. Serial No. 872,880.

To all whom it may concern:

Be it known that I, JOHN H. DALE, a citizen of the United States, residing at the city of New York, in the borough of Manhattan and State of New York, have invented certain new and useful Improvements in Electric-Lighting Fixtures, of which the following is a full, clear, and exact description.

10 This invention relates to fixtures for electric light systems.

The two systems of electric lighting in common use may be generally characterized as direct and indirect, the former permitting 15 the rays from the lamp to strike directly upon the surface to be illuminated, while in the latter the path of the rays is obstructed by an inverted shade or globe which depends from the ceiling, and which may be 20 opaque or translucent, to wholly or partially deflect or diffuse the rays to give a more subdued, but uniform, source of illumination.

The common form of fixture for direct 25 lighting as used in office buildings and the like, comprises a shell which is secured to the ceiling and which carries a lamp socket receiving the lamp, the rays of which are directed downwardly by any of the well 30 known types of bell-shaped shades. In indirect lighting systems, however, the lamp is supported at a considerable distance from the ceiling, and positioned beneath the lamp 35 is an inverted dome-shaped shade or canopy which is held in suspension by chains attached at their upper ends to the structure at a point adjacent the ceiling. It is now 40 becoming customary to install one or the other of these lighting systems in accordance with the desire of the tenants, but it frequently happens that after one system is 45 installed, the same, or a new occupant, requests it to be changed to suit his particular needs. Heretofore, in so far as I am aware, this has required the complete pulling 50 out of one fixture and the replacing of it by another, which is suited for the desired purposes, which changes can only be effected at a considerable expense of time and labor.

55 The objects of this invention are, therefore, to provide a fixture which can be readily converted from one form to the other without disturbing any of the parts of the fixture which are permanently secured to the ceiling or like supporting structure, the change being easily and readily effected

without requiring the services of a skilled electrician to make any alterations in the electrical connections, and the fixture when in use with either system being complete in itself and of a highly ornamental and attractive appearance.

With these and other objects in view which will be obvious to one skilled in the art from the detailed description hereafter to follow, my invention consists of the constructions and combinations described in detail and particularly pointed out in the appended claims.

In the accompanying drawings: Figure 1 shows a lighting fixture constructed in accordance with the principles of my invention assembled for use in an indirect lighting system; Fig. 2 is an enlarged vertical section through the upper portion of the fixture shown in Fig. 1; and Fig. 3 is a detail showing the manner in which a portion of the fixture may be utilized for direct lighting.

Adapted to be secured to a ceiling or like supporting structure is a spider 1 having an annular flange 2, the upper edge of which is adapted to rest against the ceiling or like supporting structure. Passing through a centrally disposed opening in the spider is a pipe 3 to which the spider is secured by a nut 4, the pipe 3 being the ordinary outlet which is ordinarily used in lighting systems through which the conductors are led, which supply the current for the lamp. These spiders are generally placed in position when a building is being wired and are permanently secured in place over each outlet, while the other portions of the fixtures are adapted to be secured thereto after the building is completed and ready for occupancy, since the further installation requires merely the conductors to be spliced together and does not require the use of any tools, as will be apparent from the description hereinafter to follow. Depending from this spider is a substantially cone-shaped shell 5 which is provided with an annular flange 6 adapted to fit over a portion of the flange of the spider to centrally position it and hold it against lateral movement. The shell is detachably secured to the spider by means of the screws 7 which pass through key-hole shaped slots (not shown) in the shell, which is then turned to bring the smaller portion of the slots into engagement with the shank of the screws, after which the screws are

then tightened until their heads are clamped against the walls of the slots.

Projecting inwardly from the interior of the shell is a strap or spar 7 which forms the supporting structure for a pull socket 8, the chain 9 of which passes through the usual eyelet 10 provided in the surface of the shell, the chain having attached to it an extension cord 11 by which the pull socket 8 may be operated. The apex of the shell is cut away and the opening which would otherwise occur is closed by a flat circular disk 12, preferably integral with the side walls of the cone. This disk forms a seat for a porcelain block 13 disposed in the interior of the shell and which is secured in place on the disk by screws 14 passing up through laterally disposed lugs on the block (see Fig. 3). This porcelain block forms the receptacle for the circuit terminals and the lamp socket of the usual type, the terminals being connected by the usual leads in series with the pull socket and two conductive leads passing down through the outlet pipe 3. The seat 12 is provided with a centrally disposed opening, giving free access to the lamp socket which is adapted to receive the ordinary type of electrical lamp 15 when direct lighting is desired (see Fig. 3). The exterior surface of the cone-shaped shell adjacent the seat 12 is preferably recessed to form an annular groove or sleeve 16 over which a shade holder 17 is adapted to slip, the shade holder being of the usual type, and is held in place by the bayonet slots 18 therein, which lock with the screws 19 projecting radially from the groove 16. The structure thus far described provides a fixture for use in a direct lighting system as the shade holder is adapted to support the usual form of shade, directing the rays of light from the lamp downwardly upon the surface or space to be illuminated and is, in itself, a complete fixture.

In an indirect lighting system the form of fixture shown in Figs. 1 and 2 is utilized and requires only the removal of the shade holder 17, after which the other portions of the fixture may be assembled without any disturbance of the parts which are already in position. In the best practical construction of my invention, this is accomplished by providing a hollow cup-shaped shell 20 of a size to fit over the groove or sleeve 16 to which it may be detachably secured by the bayonet slots 21 in the shell, and the screws 19, as before. This cup-shaped member is provided in its lower end with a central opening through which the shank or sleeve 22 of a tubular member 22 is adapted to fit and which is secured thereto by a nut 23. The member 22 carries hooks 24 which form supports for chains 25, the lower ends of which support a dome shaped shade or canopy 26, which may be of opaque material when an

indirect lighting system is used, or may be translucent where a semi-indirect system is desired. A second lamp socket 27, which is adapted to receive a lamp 28 to furnish the source of illumination is rigidly supported upon a hollow tubular member 29 which at its upper end is connected by the links 30 to the tubular member 22. This lamp socket is adapted to be connected to the lamp socket carried by the cone-shaped shell by a plug and cord attachment, the plug 31 of which is screwed into the socket 13 in the ceiling piece. The conductors 32 leading from the plug 22 pass down through the tubular member 22 and hollow rod 29 and are connected to the lamp socket 27. It will therefore be seen that the cup-shaped shell 20 serves as a housing for the plug 31 and the exposed ends of the lamp socket 13, together with the length of exposed conductors 32 which are necessary to make the attachment. When the parts are assembled as shown in Fig. 1, the cup 20 practically forms a continuation of the cone-shaped shell so that there are no exposed electrical connections or make-shift connections to mar the beauty of the fixture.

To reconvert the fixture for use with a direct lighting system, it is only necessary to loosen the screws 19 which hold the shell 20 in place, and the entire structure including the chain, canopy, socket 27, and rod 29 may be removed as a single unit and the shade holder 17 replaced, which changes may be made without the services of a skilled electrician, and requiring no tools other than a means for loosening and tightening the screws 19 which hold the shade 17 and shell 20 in place. The extreme simplicity of the convertibility of the fixture is one of its decided advantages, since it permits the portion of the fixture to be used for direct lighting to be installed throughout the whole building and where desired the additional unit may be supplied if indirect lighting is desired, the installation being uniform and standard throughout the entire building.

While I have shown one specific construction of a convertible fixture for indirect and direct lighting systems, yet in so far as I am aware it is novel with me to provide one unit which may be permanently attached to the ceiling or like supporting structure and a second unit comprising a unitary structure which may be detachably secured to the first unit to provide an indirect lighting system, and it is not my intention to limit the invention to the particular form of connections described but only by the scope of the appended claims.

The shell 20 has another important function apart from its use with an indirect lighting system. It will be seen that by removing the inverted shade 26 and the chains 25 a drop light is provided which is of ex-

tremely attractive appearance since the electrical connections including the plug 31 and socket 12 are entirely concealed by the tubular shell 20, and it is my intention to 5 cover this feature of the invention apart from its particular utility with indirect lighting systems.

I claim:

1. A lighting fixture for direct and indirect lighting systems comprising two units, one of which is adapted to be secured to a ceiling or the like and carries means for receiving a lamp, shade, and shade holder to constitute a complete fixture for direct lighting, the other of said units being adapted to be detachably secured to said first named unit in lieu of said shade and shade holder, and comprises connections for supporting a lamp and inverted shade at a distance 15 from said first named unit and constituting with said first named unit a complete fixture for indirect lighting.

2. A lighting fixture comprising a member adapted to be supported from the ceiling and carrying a lamp socket, a second lamp socket, electrical connections therefor including a cord and a plug adapted to fit into said first named socket, and a housing for said plug detachably secured to said first 20 named member.

3. A lighting fixture comprising a member adapted to be supported from the ceiling and carrying a lamp socket, a second lamp socket, electrical connections therefor including a cord and a plug adapted to fit into said first named socket, a housing for said plug detachably secured to said first named member, an inverted shade, and members for supporting said shade from 35 said housing.

4. A lighting fixture comprising an inverted substantially cone-shaped shell adapted to be supported from a ceiling and carrying a lamp socket in its downwardly extending narrow end, a second lamp socket,

electrical connections therefor including a cord and a plug adapted to fit into said first named socket, and a housing for said plug fitting over and detachably secured to the narrow end of said cone-shaped member. 50

5. A lighting fixture comprising an inverted substantially cone-shaped shell adapted to be supported from a ceiling and carrying a lamp socket in its downwardly extending narrow end, a second lamp socket, 55 electrical connections therefor including a cord and a plug adapted to fit into said first named socket, a housing for said plug fitting over and detachably secured to the narrow end of said cone-shaped member, an inverted shade, and members for supporting said shade connected to said housing.

6. A lighting fixture comprising an inverted, hollow, substantially cone-shaped member adapted to be supported from a 65 ceiling and carrying a lamp socket in its downwardly extending narrow end, a second lamp socket, a cord and plug attachment therefor, said plug fitting into said first named socket, and a housing for said 70 plug and socket comprising a cup-shaped shell fitting over and detachably secured to the end of said member and virtually forming a continuation thereof.

7. A lighting fixture for direct and indirect lighting systems consisting of two units, one of said units being rigidly supported from the ceiling and carrying an electric lamp socket in its lower end, the other of said units comprising an inverted shade, 80 supporting members therefor, a second lamp socket and its electrical connections for connecting it to said first named socket.

In witness whereof, I subscribe my signature, in the presence of two witnesses.

JOHN H. DALE.
